UNITED STATES PATENT OFFICE.

GEORGE H. HUTTON, JR., OF BALTIMORE, MARYLAND.

REAR SEAT FOR VEHICLES.

No. 830,325.

Specification of Letters Patent.

Patented Sept. 4, 1906.

Application filed November 16, 1905. Serial No. 287,674.

To all whom it may concern:

Be it known that I, GEORGE H. HUTTON, Jr., a citizen of the United States, residing at Baltimore, in the State of Maryland, have invented certain new and useful Improvements 5 in Footmen's Rear Seats for Vehicles, of which the following is a specification.

This invention relates to an improved footman's rear seat for light vehicles.

10 The object of the invention is to provide a foldable seat for attachment to the rear end of a vehicle-body and capable of taking a position projecting back beyond the body, folding forward and downward into the said body, and also adapted to be entirely lifted from its position.

The invention is illustrated in the accompanying drawings, in which—

Figure 1 is a side elevation showing a vehicle-body and the footman's seat projecting back of the rear end. Fig. 2 is a like view of a body, but showing the footman's seat partly folded. Fig. 3 is a vertical sectional elevation of the seat in its upright position 25 and shows the inner side of one jointed standard. Fig. 4 is a top view of the seat as seen when in the position which it has in Fig. 3. Fig. 5 is a detail view, on a larger scale, of the coupling-joint at the base. Fig. 6 is a sectional view of the coupling-joint on the line 6 6 in Fig. 5. Fig. 7 is a view of the upper jointed part of a standard and arm and shows the outer side of same.

30 The improved seat may be used on any style or design of vehicle-body.

The letter A designates a vehicle-body, b the rear end of the body, and c a wood bar secured on the inside at the bottom where the end-board joins the bottom of the body.

40 The improved seat is supported by two standards d, both of which are seen in the top plan view, Fig. 4. Each standard d is coupled to a stationary metal base e, which is permanently secured in the bottom of the 45 vehicle-body, a metal base e being in each of the two rear corners and secured by a bolt f and a screw f'. The metal base comprises two side walls e', which are cast in an integral piece and spaced apart, and has a pivot-bolt e'', attached to the two walls and extending across the said space. The metal base also has at its rear end a shoulder e''. Each standard has at its lower end a coupling-jaw 55 g, which has an open slot g', that takes over the pivot-bolt e'' on the base, and the jaw g sets down into the space between the two

walls e'. At the rear of the coupling-jaw the standard has a heel h, which when the standard is in vertical position sets upon the shoulder e'' of the base and sustains the seat. 60 The coupling-joint thus constructed enables the standard d to stand upright and also to tilt forward, as indicated by broken lines in Fig. 5. When the standard has been tilted forward to an angle of about forty-five degrees, 65 the open slot g' in the coupling-jaw will be in vertical position, and then the seat, with its standards, may be lifted entirely from position, and thus removed from the vehicle-body. When the standard has been tilted forward 70 and also downward as far as it will go, the seat will be inclosed within the box part of the vehicle-body.

In addition to the two standards d the seat also comprises the two arms I, each arm being 75 united by a pivot-joint j to one of the standards d. Each end of the seat therefore has a standard d and arm I and two pivot-joints e'' and j.

The arm I has two curved bars, the upper 80 bar k and the lower bar l, which have one end united near the pivot j and the other ends united and forming an upward-curved point where the back rail m is secured which extends across from one arm to the other arm. 85 (See Fig. 4.) The two arms I also have an attached bar n, which extends across between the lower curved bars l. Each arm has a stop-shoulder j' on the lower curved bar l, which abuts against a similar stop-shoulder 90 j'' on the upper part d' of the standard d. From this construction it is obvious that the arms I may tilt on the pivot j up and forward; but as the stop-shoulders are below the pivot j they will prevent the arm I from tilting 95 downward.

A front bar o (see Fig. 3) extends across between the two standards d, the ends of the bar being securely fastened to said standards.

The seat proper (designated p) is to be 100 made, preferably, of canvas or some other suitable flexible material and is secured to the bar n on the arms and the bar o on the standards. When the parts of the improved seat have the position for use shown in Fig. 105 1, the canvas seat p will be stretched, and when the arms I are folded forward and downward, as shown in Fig. 2, the canvas seat will also fold.

The operation of the device has been explained in connection with the description.

Having thus described my invention, what

I claim as new, and desire to secure by Letters Patent, is—

1. The herein-described rear seat for vehicle-bodies, comprising two metal bases permanently secured in the bottom of the vehicle-body; two standards each jointed to one of said metal bases; a front bar extending horizontally between said two standards and secured thereto; an arm jointed to the upper part of each of said standards and adapted to project back beyond the rear of the vehicle-body; a back bar extending horizontally between the said two arms and connecting them; and a seat of flexible material secured both to the front bar and the back bar.
2. A rear seat for vehicle-bodies having in combination two metal bases, *e*, comprising side walls spaced apart, a pivot-bolt across the space, and a shoulder, *e*³, at the rear of the said pivot; two standards jointed to said pivot-bolts and each standard provided at its rear with a heel which sets upon said base-

shoulder; an arm jointed to each standard and provided below said joint with stop-shoulders and projecting back beyond the rear of the vehicle-body, and a seat supported by the standards and arms. 25

3. A foldable rear seat for vehicle-bodies having in combination two metal bases secured in the bottom of the vehicle-body and each having a pivot-bolt; two standards each having a coupling-jaw provided with an open slot which takes over the pivot-bolt and forms a jointed connection; an arm jointed to each standard and adapted to project back beyond the rear of the vehicle-body and to fold up and forward; a back rail connecting the two arms; and a flexible seat secured between the standards and arms. 30 35 40

In testimony whereof I affix my signature in presence of two witnesses.

GEORGE H. HUTTON, JR.
